United States Patent Office

Des. 203,783
Patented Feb. 15, 1966

203,783

GARMENT HANGER

John H. Batts, Grand Rapids, Mich., assignor to John Thomas Batts, Inc., Zeeland, Mich., a corporation of Michigan

Filed Mar. 12, 1965, Ser. No. 84,246

Term of patent 14 years

(Cl. D80—8)

FIG. 1.

FIG. 2

FIG. 3.

FIG. 4.

FIG. 5.

FIG. 1 is a front elevational view of a hanger showing my new design;

FIG. 2 is a top plan view thereof;

FIG. 3 is an end elevational view thereof;

FIG. 4 is an enlarged fragmentary elevational view of the end of one arm thereof; and

FIG. 5 is a bottom plan view of the end shown in FIG. 4.

I claim:

The ornamental design for a garment hanger, substantially as shown.
